CLAIM

The ornamental design for an accumulator, as shown and described.

DESCRIPTION

Cross reference is made to copending U.S. design patent application Ser. No. 29/576,267 entitled "Accumulator" by Greiner, Rinaldo, which was filed on Sep. 1, 2016; U.S. design patent application Ser. No. 29/576,271 entitled "Accumulator" by Greiner, Rinaldo, which was filed on Sep. 1, 2016; U.S. design patent application Ser. No. 29/623,868 entitled "Accumulator" by Schumacher, Christoph, which was filed on even date herewith; U.S. design patent application Ser. No. 29/623,876 entitled "Accumulator" by Schumacher, Christoph, which was filed on even date herewith; and U.S. design patent application Ser. No. 29/623,881 entitled "Accumulator" by Schumacher, Christoph, which was filed on even date herewith.

FIG. 1 is a perspective view of an accumulator showing my new design;

FIG. 2 is a top plan view of the accumulator of FIG. 1; FIG. 3 is a bottom plan view of the accumulator of FIG. 1; FIG. 4 is a right side elevational view of the accumulator of FIG. 1;

FIG. 5 is a left side elevational view of the accumulator of FIG. 1;

FIG. 6 is a front elevational view of the accumulator of FIG. 1; and,

FIG. 7 is a rear elevational view of the accumulator of FIG. 1.

The broken lines shown in the drawings illustrate portions of the accumulator that form no part of the claimed design.

1 Claim, 12 Drawing Sheets
